DESIGN FOR A MAGNIFYING DEVICE

Clinton H. Kibbe, New York, N. Y.

Application December 2, 1938, Serial No. 81,521

Term of patent 14 years

To whom it may concern:

Be it known that I, Clinton H. Kibbe, a citizen of the United States, residing at No. 87 Hamilton Place, New York city, in the county of New York and State of New York, have invented a new, original, and ornamental Design for Magnifying Devices, of which the following is a specification, reference being had to the accompanying drawing, forming part thereof.

Fig. 1 is a side elevational view of a magnifying device showing my new design; and
Fig. 2 is a plan view of the same.

I claim:

The ornamental design for a magnifying device, as shown.

CLINTON H. KIBBE.
